UNITED STATES PATENT OFFICE.

JOHN H. ANDERSON, OF SHELBY, NEBRASKA.

HYDRAULIC DREDGE.

SPECIFICATION forming part of Letters Patent No. 294,303, dated February 26, 1884.

Application filed September 20, 1883. (No model.)

To all whom it may concern:

Be it known that I, JOHN H. ANDERSON, of Shelby, in the county of Polk and State of Nebraska, have invented a new and Improved 5 Hydraulic Dredge, of which the following is a full, clear, and exact description.

The object of the invention is to improve the operation of hydraulic dredge-tubes, so that the water which is forced through them 10 may be made to work up against the under part of the sediment as the tube-nose passes beneath it, and thus effectually divide and scatter it, while valves prevent any backflow of water into the tube.

Reference is to be had to the accompanying 15 drawings, forming part of this specification, in which similar letters of reference indicate corresponding parts in all the figures.

Figure 1 is a side elevation of my hydraulic 20 dredge, illustrating its mode of operation. Fig. 2 is a longitudinal sectional elevation of the dredging-pipe, and Fig. 3 is a top or plan view of the same. Fig. 4 is a side elevation 25 of the bearings for the trunnions of the dredging-pipe, and Fig. 5 is a top or plan view of the same.

A is the forward part of the steamboat, on 30 the bow a' of which the dredging-pipe B is mounted, and in which are the steam-pump C, the windlass D, and apparatus for their operation. The boat A is preferably propelled by steam, in which case the steam-boiler is used for the purpose of supplying steam for the operation of the pump C; but the boat may be 35 propelled by any other known method—such as by a cable attached to an anchorage and operated by a windlass. The dredge-pipe B is mounted by the trunnions b in the bearings b^2 , by which it is adapted to a vertical motion, 40 and also secured to the boat by the cap b^7 and bolts b^8 . The outer part of the dredge-pipe B is supported and adjusted by a chain or rope, F, which is attached to dredge-pipe B at g , and, passing over the pulley g^2 , is secured to 45 a windlass, D. The outer end of the dredge-pipe B is formed into a shovel-shaped nose, b^3 , made sharp at its extremity b^5 and adapted to penetrate the material in which it is to be operated. On the upper side of the nose b^3 are 50 valves b^4 b^6 , opening outward and adapted as outlets for the water forced through the dredge-

pipe B. The inner and upper end of the dredge-pipe B is connected with the steam-pump C by means of the hose E and coupling e .

C is a steam-pump of any ordinary construction, operated with steam supplied from the boiler ordinarily used for supplying steam to the engine for propelling the boat or from a boiler provided for the purpose.

The operation is as follows: The boat A is 60 placed in position near to the bar or other deposit which it is required to remove, and by means of the windlass D and chain F the dredge-pipe or dredge-pipes B are lowered and adjusted, so that a forward motion of the boat 65 A will cause them to penetrate the material of the bar. The boat is then made to move forward, and at the same time the pump C is put in operation, and thus a stream of water is forced through the dredge-pipes B and valves 70 b^4 against the material composing the bar, which is thus excavated and scattered and caused to mingle with the current of the stream, and is by it carried away. The dredge-pipes A are 75 adjusted from time to time by means of the windlass D and chain or rope F, and the boat is advanced or otherwise adjusted, and the operation is continued until the deposit is entirely removed.

The advantages of my hydraulic dredge are 80 the great facility with which bars and sedimentary deposits may be removed therewith, the simplicity of its construction, and the ease with which it may be moved from place to place and operated.

Having thus described my invention, what I 85 claim as new, and desire to secure by Letters Patent, is—

1. A hydraulic dredge-tube having its nose closed at the end and provided on top with 90 upwardly-opening valves b , as and for the purpose specified.

2. The dredge-pipe B, constructed substantially as described, with the nose b^3 , valves b^4 , and trunnions b , and adapted to be secured to 95 the boat A and to have a vertical motion about the trunnions b and to carry a stream of water, as set forth.

JOHN H. ANDERSON.
